UNITED STATES PATENT OFFICE

132,634

DESIGN FOR A LAPEL PIN OR SIMILAR ARTICLE

Paul M. Allen, Richmond, Va., assignor of one-third to Paul W. Vaughan and one-third to James E. Terry, both of Richmond, Va.

Application January 20, 1942, Serial No. 105,333

Term of patent 3½ years

To all whom it may concern:

Be it known that I, Paul M. Allen, a citizen of the United States, residing at Richmond, in the county of Henrico and State of Virginia, have invented a new, original, and ornamental Design for a Lapel Pin or Similar Article, of which the following is a specification, reference being had to the accompanying drawing, forming part thereof.

I claim:

The ornamental design for a lapel pin or similar article, as shown.

PAUL M. ALLEN.
